UNITED STATES PATENT OFFICE.

BENJAMIN BERNARD DEITEL, OF BROOKLYN, NEW YORK.

DESIGN FOR A VANITY CASE.

Application filed October 30, 1928. Serial No. 28,691. Term of patent 7 years.

To all whom it may concern:

Be it known that I, BENJAMIN BERNARD DEITEL, a citizen of the United States, and a resident of Brooklyn, Kings County, State of New York, have invented a new, original, and ornamental Design for Vanity Case, of which the following is a specification, reference being had to the accompanying drawing, forming part thereof.

showing my new design. Figure 2 is a side view of the same vanity case.

The vanity case is shaped to simulate a book with a "futuristic" ornamentation on one or both sides of the cover.

I claim:

The ornamental design for a vanity case as shown and described.

BENJAMIN BERNARD DEITEL.
